(57) **CLAIM**

We claim the ornamental design for an aerosol generator, as shown and described.

DESCRIPTION

FIG. 1 is a top front perspective view of an aerosol generator showing the claimed design;

FIG. 2 is a bottom rear perspective view thereof;

FIG. 3 is a top view thereof;

FIG. 4 is a bottom view thereof;

FIG. 5 is a front view thereof;

FIG. 6 is a rear view thereof;

(Continued)

FIG. 7 is a left view thereof; and,
 FIG. 8 is a right view thereof.
 The broken lines in the drawings illustrate portions of the
 aerosol generator that form no part of the claimed design.
